United States Patent Office

Des. 188,452
Patented July 19, 1960

188,452

ASH TRAY

John Gottfried, 2123½ Summit St., Toledo, Ohio

Filed Oct. 8, 1959, Ser. No. 57,864

Term of patent 14 years

(Cl. D85—2)

Fig. 1 is a top plan view of an ash tray, embodying my new design;

Fig. 2 is a cross-sectional view taken along the line II—II of Fig. 1; and

Fig. 3 is an edge view looking from the right of Fig. 1.

I claim:

The ornamental design for an ash tray, substantially as shown.
